(57) **CLAIM**

The ornamental design for a broom, as shown and described.

DESCRIPTION

FIGS. 1 and 2 are perspective views of the head of broom in accordance with the present invention;

FIG. 3 is a top view of the head of the broom;

FIG. 4 is a front end view of the head of the broom;

FIG. 5 is a side view, the opposite side being a mirror image thereof; and,

FIG. 6 is a back end view of the head of the broom.

The bottom of the broom head is covered by bristles, and thus is not normally seen when the product is purchased or used.

The broken line showing of the “Libman” trademark appearing in the drawings is for illustrative purposes only and forms no part of the claimed design.
